(57) **CLAIM**

The ornamental design for a guide wire as shown and described.

DESCRIPTION

FIG. 1 is a perspective view of the guide wire; FIG. 2 is a front elevational view thereof; FIG. 3 is a left-side elevational view thereof; FIG. 4 is a right-side elevational view thereof; FIG. 5 is a top plan view thereof; and, FIG. 6 is a bottom plan view thereof.

The dot-dash broken lines represent the bounds of the claimed design while all other broken lines in the drawings show portions of the guide wire that form no part of the claimed design. The broken break lines in the drawings indicate that the appearance of any portion of the article between the broken break lines forms no part of the claimed design.

1 Claim, 3 Drawing Sheets
